UNITED STATES PATENT OFFICE.

ADOLF HAHN, OF FAR ROCKAWAY, NEW YORK.

DESIGN FOR AN OPERA GLASS OR SIMILAR ARTICLE.

Application filed April 29, 1924. Serial No. 9,437. Term of patent 7 years.

To all whom it may concern:

Be it known that I, ADOLF HAHN, a citizen of Germany, residing at Far Rockaway, Queens County, State of New York, have invented a new, original, and ornamental Design for an Opera Glass or Similar Article, of which the following is a specification, reference being had to the accompanying drawing, forming part hereof, in which—

Fig. 1 is a side elevation of an opera glass showing my new design and

Fig. 2 is a top plan view of the same.

I claim:—

The ornamental design for an opera glass or similar article as shown.

Signed at New York city, N. Y., this 23rd day of April, 1924.

ADOLF HAHN.

Witnesses:

MAURICE BLOCK,
JOHN J. LYNCH.
